UNITED STATES PATENT OFFICE.

JAMES T. COWLEY, OF SYRACUSE, NEW YORK, ASSIGNOR TO THE LAMSON COMPANY, OF SYRACUSE, NEW YORK, A CORPORATION OF MASSACHUSETTS.

PNEUMATIC POWER CONTROL.

Application filed July 12, 1923. Serial No. 651,064.

To all whom it may concern:

Be it known that I, JAMES T. COWLEY, a citizen of the United States of America, and resident of Syracuse, in the county of Onondaga and State of New York, have invented new and useful Improvements in Pneumatic Power Controls, of which the following is a specification.

This invention relates to power control apparatus for pneumatic despatch systems of the general type of that disclosed in the patent to Libby, 968,576, August 30, 1910 and comprising a main valve operated by a diaphragm which moves in accordance with pressure variations in the transmission line.

Principal objects of the present invention are to provide a controlling apparatus of the above type which is very sensitive both to the slight decrease in pressure in the transmission line occasioned by the introduction of a carrier and to the slight increase in pressure in the line resulting from discharge of a carrier; to provide such an apparatus having means for closing the main valve quickly upon such slight decrease in pressure incident to the delivery of a carrier or optionally to permit it to close more slowly and in accordance with a timing device and irrespective of the discharge of a carrier from the transmission line, but so designed that the valve will not flutter or chatter under rapid pressure variations; and to provide controlling means for the main valve operating diaphragm which imposes substantially no load upon said diaphragm so that the latter may be sensitively responsive to slight pressure variations and capable of moving the valve quickly and reliably.

In the accompanying drawing a preferred embodiment of the invention is illustrated by way of example and in such drawings:

Fig. 1 is a side elevation, partly in vertical section and partly diagrammatic, illustrating a controlling apparatus embodying the present invention;

Fig. 2 is a cross section on the line 2—2 of Fig. 1, certain parts being indicated diagrammatically; and

Fig. 3 is a fragmentary vertical section through the right hand portion of the device shown in Fig. 1 illustrating details of construction.

Referring to the drawings, the power controlling apparatus is shown as comprising a housing consisting of the lower part 1 and

the upper part or cover 2. The lower part 1 is provided with an outlet cavity 3 which is connected by means of a pipe 4 with the usual vacuum drum (not shown) of such a system.

A casing 5 projects into the outlet cavity 3, such casing preferably being integral with the wall of the lower part of the housing. This casing is hollow, furnishing an inlet cavity 6 which communicates by means of a pipe 7 with a transmission line of the system. Preferably the controlling apparatus is arranged at the central station of such a system and is connected to the transmission line at a point adjacent to the delivery terminal of such transmission line.

The upper and lower walls 8, 9 respectively of the casing 5 are provided with openings for the reception of the heads 10, 11 of a balanced piston valve 12. The lower head of this valve is preferably provided with a small passage 13 connecting the chambers 6 and 3 when the valve is closed. The upper head 10 of the valve has a stem 14 which slides in a suitable opening in a boss 15 projecting from the upper wall 16 of the member 1 of the housing.

This upper wall extends outwardly in the form of a substantially radial flange which terminates in a circumferential seat 17. The outer edges of a flexible diaphragm 18 are secured to the seat 17 by means of a flange member 19 forming a part of the cover 2. The central part of this diaphragm is clamped between two plates 20, 21 respectively which are secured to the upper end of the stem 14 by means of a nut 22.

The diaphragm 18 thus divides the upper part of the housing into upper and lower chambers 23, 24 respectively.

The upper chamber 23 of the housing is connected to the outlet cavity 3 by means of a passage 25 preferably extending through a boss 26 outstanding from the housing. The diaphragm is provided with an opening 27 at 27 where it crosses the passage 25 in order that the passage may not be interrupted at this point.

The lower chamber 24 is provided with a passage 28 within a boss 29 outstanding from the side wall of the housing, and this passage terminates in a port 30 opening to the atmosphere. This port is surrounded by a suitable valve seat with which a valve 31 engages for closing the port. This valve is

provided with a stem 32 which preferably forms the core of a solenoid 33. The weight of the valve 31 with its stem is ordinarily sufficient to hold it normally against its seat although a spring may be provided for seating it if desired.

A passage 34 (Fig. 3), extends through a boss 35 arranged at a suitable point on the flanged portion of the housing and connects 10 the chambers 23 and 24. This passage is controlled by a needle valve 36 which may be set so as to provide for the passage of air at any desired rate from one of the chambers to the other.

15 A slideable post or stem 37 is arranged coaxially with the stem 14 of the main valve 12 and is guided for vertical movement by passing through a bore in a threaded sleeve 38 mounted in an opening at the central part of 20 the cover 2. A spring 39 encircles the stem 37, and bears at its upper end against the inner surface of the sleeve 38. Its other end rests upon a nut 40 secured to the lower end of the stem 37. This spring is normally 25 under tension and tends to move the stem 37 downwardly so as to cause it to press upon the upper end of the stem 14, thus holding the diaphragm 18 and the main valve 12 in the position shown in Fig. 2.

30 An auxiliary or control motor 41 is mounted upon the cover member 2. This auxiliary motor preferably comprises a housing, one part of which is integral with the cover, and which comprises the upper and lower chambers 42, 43 respectively separated by the flexible diaphragm 44. The lower chamber 43 communicates with the atmosphere by means of a small port 45 while the upper chamber communicates with the transmission line of 40 the system by means of a pipe 46.

45 The diaphragm 44 is furnished with a stem 47 encircled by a spring 48. This spring is of just sufficient stiffness to hold the diaphragm in substantially horizontal position against the pressure of the atmosphere in the lower chamber 43 when conditions in the transmission line are normal and no carrier is passing but to permit the diaphragm to bulge upwardly upon the slight 50 decrease in pressure in the transmission line incident to the introduction of a carrier therein. The upper end of the stem 47 underlies the lowermost of a pair of resilient contact fingers 48, 49 respectively secured to 55 an insulating block 50. These fingers are provided with opposed contacts which are normally separated from each other but which may be caused to contact by upward movement of the stem 47.

60 A conducting wire 51 extends from the resilient finger 49 to one terminal of the solenoid 33. Preferably a battery 52 or other source of electrical energy is interposed in this wire. The other resilient finger 48 is 65 connected by means of a wire 53 to a resil-

ient finger 54 mounted on an insulating block 55. A second resilient finger 56 is mounted upon an insulating block 57 and normally engages the finger 54. Preferably these fingers are inclined upwardly from 70 their supporting blocks to their points of engagement as indicated in Fig. 2. A conducting wire 58 leads from the finger 56 to the other terminal of the solenoid.

A circuit breaker 59 is arranged immediately beneath the point of contact of the fingers 54 and 56. This circuit breaker is a tapering plug or wedge of insulating material carried by the upper end of a slide member 60 arranged to reciprocate in a bore 61 formed in a boss 62 carried by the cover 2. A spring 63 is secured to the outer surface of the boss and bears against the side of the slide member 60 so as frictionally to retain the latter in any position in which it may be placed.

The slide member 60 is furnished with an axially elongate slot or recess 64 in its side and a finger or lug 65 carried by the upper end of the stem or post 37 projects into this recess.

A second auxiliary or control motor 66 is also carried by the cover 2 (Fig. 1). This second auxiliary motor is of substantially the same construction as that of the motor 41, comprising the upper and lower chambers 67, 68 respectively separated by the flexible diaphragm 69. The lower chamber 68 communicates with the atmosphere by means of a small port 70, while the upper 100 chamber is connected to the transmission line by means of a pipe 71.

The diaphragm 69 is provided with a stem 72 encircled by a spring 73. This spring is somewhat heavier than the spring 48 of the motor 41 so that the diaphragm 69 is not moved to any substantial extent when a carrier is first introduced into the transmission tube.

75 The upper end of the stem 72 underlies the lowermost of a pair of resilient fingers 74, 75 carried by an insulating block 76. These fingers are provided with cooperating contact members normally spaced apart but engageable upon upward movement of the stem 72. The upper finger 75 is connected by a wire 77 to the conducting wire 53 previously described while the lower finger 74 is connected by a wire 78 to the conductor 58.

80 The operation of the device is substantially as follows, it being assumed that the parts are in the position shown in Figs. 1 and 2, that no carrier is in the transmission line and that the needle valve 36 has been so set as to permit a rapid movement of air from the chamber 24 of the housing to the chamber 23. When the parts are thus positioned a slight flow of air is maintained in the transmission tube, being drawn through the passage 13 in the lower

head 11 of the main valve. This lowers the pressure in the transmission tube somewhat below atmospheric pressure and this low pressure is also maintained in the chambers 5 42 and 67 of the auxiliary motors 41 and 66 respectively. The upper chamber 23 of the housing being in direct communication with the outlet chamber 3, is also under low pressure, substantially lower than that of 10 the auxiliary motors.

When a carrier is introduced into the transmission line its resistance to movement results in a further decrease in pressure in the transmission line. This immediately 15 causes the diaphragm 44 of the auxiliary motor 41 to rise, thus completing an electrical circuit through the contacts carried by the fingers 48 and 49. This circuit includes the wire 51, the battery or other source of energy 20 52, the solenoid 33, the wire 58, the resilient fingers 56, 54, and the wire 53. Immediately upon completing this circuit, the solenoid 33 is energized, lifting the valve 31 and admitting atmospheric pressure 25 beneath the diaphragm 18. The latter rises very quickly, thus opening the main valve 12 and admitting a rush of air from the transmission line through the outlet passage 3 to the vacuum drum. This sudden 30 rush of air lowers the pressure in the transmission line to a very marked degree, thus rapidly moving the carrier toward its destination and decreasing the pressure in the auxiliary motor 66 sufficiently to raise the 35 diaphragm 69 and close the contacts carried by the members 74 and 75. This completes an electrical circuit through the wire 78, the wire 58, the solenoid 33, the wire 51, the battery 52, the contact fingers 49 40 and 48 which are still in engagement, the wire 53, and the wire 77.

As the main valve approaches its upper limit of movement the lug 65 comes into contact with the upper end wall of the recess 45 64, thus raising the slide member 60 and thrusting the plug 59 between the contact fingers 54, 56. This immediately breaks the circuit first described through these fingers and would result, were it not 50 for the closure of the circuit between the fingers 74 and 75, in deenergizing the solenoid 53 and closing the valve 31. However, as the circuit is complete at this time 55 through the fingers 74 and 75, the solenoid remains active and the valve 31 is kept open.

When the carrier is delivered from the transmission line and the pressure in the latter drops slightly, the spring 73 of the auxiliary motor 66 returns the stem 72 to 60 normal position, thus braking the circuit between the fingers 74 and 75, deenergizing the solenoid, and permitting valve 31 to close.

65 As soon as the valve 31 is closed the

spring 39 begins to act to depress the diaphragm 18, this action being controlled by the rate at which the air in the chamber 24 is able to escape from the passage 34 into the chamber 23. As above stated, the needle valve 36 is so set as to permit a rapid movement of the air from the chamber 24 so that the main valve 12 is rapidly returned to its seat, thus stopping the flow in the transmission line. As the diaphragm 18 approaches 70 the lower limit of its movement, the lug 65 engages the lower wall of the recess 64 and restores the slide 60 to normal position, permitting the fingers 54, 56 to come into contact. As the pressure in the transmission line is now restored to normal the diaphragm 44 reassumes the position shown in Fig. 2, breaking the contact between the fingers 48 and 49 and restoring the system 75 to normal condition.

The controlling valve 31 of the main valve actuating motor is very sensitively controlled by the slight decrease in pressure in the transmission line incident to the introduction of a carrier, but the main valve may be 80 restored to normal position by the slight increase in the pressure in the transmission line incident to the delivery of a carrier, although at such time the pressure in the transmission line is far below that necessary 85 initially to open said valve. The device thus operates independently of any predetermined timing action to open the main valve upon the introduction of a carrier into the transmission line and to close the 90 main valve quickly after the discharge of the last carrier therefrom. The carriers are thus moved to their destination with certainty and all danger of premature stoppage 95 of the air supply before the last carrier has been discharged is eliminated.

While the complete device as above described is preferred, it is possible, by eliminating the second auxiliary motor 66 with its associated parts, to employ the controlling device to advantage when it is desired to have the main valve close a predetermined interval after its opening.

If the second auxiliary motor 66 be eliminated, the rising of the diaphragm 18 causes the circuit breaker 59 to break the circuit between the fingers 54 and 56 in the manner above described, but in this case the solenoid 33 is immediately deenergized and the controlling valve 31 is closed. By setting the 110 needle valve 36 at the proper point, the return of the diaphragm 18 to its normal position, and the closing of the main valve may be caused to take place after almost any desired predetermined interval regardless of 115 the presence or absence of a carrier in the transmission line. If under such circumstances the main valve should be closed prior to the delivery of the last carrier, the continued low pressure in the transmission line 120 125 130

will again actuate the auxiliary motor 41, thus reenergizing the solenoid and causing the main diaphragm 18 with the valve 12 to rise, thus again breaking the circuit and closing a repetition of the cycle of movement.

The apparatus described is of relatively simple construction, reliable in operation, and is very effective in conserving the air supply and preventing waste of power in the transmission system.

I claim:

1. Power control apparatus for pneumatic dispatch systems comprising a main valve, a motor for operating it, means operative upon the occurrence of a slight decrease in pressure in the system to initiate operation of the motor to open the valve, and independent means operative upon a slight subsequent increase in pressure in the system for initiating operation of the motor to close the valve.

2. Power control apparatus for a pneumatic dispatch system having a transmission line, comprising a main valve, a pneumatic motor for opening and closing the valve, a controlling valve for the motor, means for actuating the controlling valve to initiate operation of the motor to open the main valve upon the decrease in pressure in the transmission line incident to the introduction of a carrier therein, and independent means for initiating closing of the main valve upon increase in pressure in the transmission line due to delivery of a carrier from the latter.

3. Power control apparatus for pneumatic dispatch systems comprising a pneumatic motor, a valve for controlling its operation, electro-magnetic means for actuating the valve, an auxiliary, pressure controlled motor, a circuit closer operable thereby to close an electrical circuit through said electro-magnetic means, and a circuit breaker actuatable by the pneumatic motor to break the circuit through the electro-magnetic means.

4. Power control apparatus for pneumatic dispatch systems comprising a pneumatic motor having a diaphragm, a valve for controlling admission of power fluid to one side of the diaphragm, electrical means for actuating the valve, an auxiliary, pressure controlled motor for completing the electrical circuit through the valve actuating means, and a slide member actuatable by the diaphragm and provided with a circuit breaker for opening the circuit through said valve actuating means.

5. Power control apparatus for pneumatic dispatch systems comprising a pneumatic motor having a diaphragm exposed on one side to reduced pressure, a valve for controlling admission of atmospheric air to the other side of the diaphragm, an electro-magnetic device for opening the valve, an auxiliary

motor operating under decreased pressure in the system to complete the circuit through the electro-magnetic means, a sliding post movable by the diaphragm upon the opening of said valve, and a circuit breaker carried by the post and operable to break the circuit through said electro-magnetic device as the diaphragm completes its movement.

6. Power control apparatus for a pneumatic dispatch system having a pneumatic motor comprising a housing having chambers separated by a movable wall, one of said chambers communicating with a low pressure space, a valve controlling admission of power fluid to the other chamber, a solenoid for actuating the valve, an auxiliary pneumatic motor having an element subject to fluctuations in pressure in the system, a circuit closer connected to said element for completing an electrical circuit through the solenoid, a slidable stem resting upon the diaphragm and movable thereby, and a circuit breaker carried by the stem for breaking the circuit through the solenoid as the diaphragm approaches the limit of its movement in one direction.

7. Power control apparatus for pneumatic dispatch systems comprising a main valve, a pneumatic motor for operating it, a normally closed controlling valve for the motor, means operable by a slight decrease in pressure in the system to open the controlling valve, means operable as the main valve approaches the limit of its opening movement to permit the controlling valve to close, and other means for holding the controlling valve open until the pressure in the system has increased.

8. Power control apparatus for a pneumatic dispatch system having a transmission tube, comprising a main valve, a pneumatic motor for actuating said main valve and a pair of pneumatic motors for controlling the operation of the first named motor, each of said pneumatic control motors having a spring pressed diaphragm exposed to the air pressure in the system and movable under fluctuations in such pressure induced by the introduction into or discharge of carriers from the transmission tube, one of said diaphragms being subject to greater spring pressure than the other.

9. Power control apparatus for pneumatic dispatch systems comprising a main valve actuating motor and a pair of auxiliary motors for controlling said main valve motor, each of said auxiliary motors normally operating in accordance with variations in pressure in the system, connections between the respective control motors and the main valve motor, and means actuated by the main valve motor for rendering the connections to one of the auxiliary motors temporarily inoperative.

10. Power control apparatus for a pneu-

- matic dispatch system having a transmission line, a valve controlling the flow of air in the line, a motor for opening and closing the valve, and a pair of pneumatic motors, each having an element movable in response to fluctuations in pressure in the line, one of said pneumatic motors being constructed and arranged to initiate valve opening movement of the first named motor when a carrier is introduced into the line, the second pneumatic motor being constructed and arranged to initiate valve closing movement of the first named motor upon discharge of a carrier from the line.
- 15 11. Power control apparatus for a pneumatic dispatch system, having a transmission line, comprising a main valve for determining the air flow in said line, a motor for actuating the valve, and a pair of auxiliary motors for controlling said first motor, said auxiliary motors operating in accordance with pressure variations in the transmission line induced by the introduction into or discharge of carriers from said line, one of said auxiliary motors being more sensitively responsive to slight pressure decrease in the system than the other.
12. Power control apparatus for pneumatic dispatch system comprising a main valve, a pneumatic motor for operating it, a controlling valve for the motor, an electro-magnetic device for moving said controlling valve, a pair of auxiliary pneumatic motors each having a diaphragm movable by pressure variations in the system, independent circuit closers connected to the diaphragms of the respective motors for closing circuits through said electro-magnetic device, and means actuated by the main motor for interrupting the circuit closed by one of the auxiliary motors.
13. Power control apparatus for pneumatic dispatch systems comprising a main valve, a pneumatic motor for operating it, a controlling valve for the motor, a pair of auxiliary motors each having a part movable in accordance with pressure fluctuations in the system, connections operable by the moving part of one of said motors for causing the controlling valve to open, means actuatable as the main valve approaches fully open position to render said connection inoperative, and means operable by the moving part of the other auxiliary motor to prevent the closing of the controlling valve.
14. Power control apparatus for pneumatic dispatch systems comprising a main pneumatic motor having a diaphragm, a normally closed controlling valve for the motor, an electro-magnetic device for opening the controlling valve, a pair of auxiliary motors each having a diaphragm movable under fluctuations in pressure in the system, electrical circuits each including said electro-magnetic device, a circuit closer connected with the diaphragm of each auxiliary motor and constructed and arranged to close one of the respective circuits through the electro-magnetic device, and a circuit breaker movable with the diaphragm of the main motor to break one of said circuits as the main valve approaches the limit of its movement in one direction.
15. Power control apparatus for pneumatic dispatch systems comprising a main motor having a reciprocable element, a movable controlling element therefor, an electro-magnetic device for moving the controlling element, a pair of auxiliary pneumatic motors each having a diaphragm movable by variations in pressure in the system, electrical circuits each including said electro-magnetic device, a slidable stem movable by the diaphragm of each auxiliary motor, a circuit closer carried by each stem and operable to close one of the circuits, respectively, through the electro-magnetic device, and a circuit breaker operable by the reciprocable element of the main motor as the latter approaches its limit of movement in one direction for interrupting one of said circuits.
16. Power control apparatus for pneumatic despatch systems comprising a pneumatic motor having a diaphragm, a controlling valve for the motor, an electro-magnetic device for operating the valve, an electrical circuit including the electro-magnetic device, a sliding circuit breaker for interrupting said circuit, said circuit breaker having an axially elongate recess, and a part actuatable by the motor and engaging the recess for actuating the circuit breaker.
17. Power control apparatus for pneumatic despatch systems comprising a pneumatic motor having a diaphragm provided with a sliding, spring pressed stem, a normally closed valve for controlling the motor, said valve having a stem constituting the core of a solenoid, an electrical circuit including the solenoid, a pair of normally contacting resilient elements in said circuit, a non-conducting circuit breaker movable between said members to interrupt the circuit, and lost motion connections between the circuit breaker and the diaphragm stem.
18. A power control apparatus for a pneumatic transmission line comprising a main valve and a plurality of pneumatic motors, one of said motors acting, upon decrease in pressure in the transmission line, to admit pressure fluid to one of the motors for actuating the main valve, and another motor acting upon increase in pressure in the transmission line, to cut off pressure fluid from the main valve actuating motor to allow the main valve to close.
19. Power control apparatus for a pneumatic transmission line comprising a valve, and electro-magnetic means operative upon

slight decrease in pressure in the transmission line due to the insertion of a carrier therein to initiate opening of the valve and upon slight increase in pressure in the transmission line incident to the discharge of a carrier therefrom to initiate closing of the valve.

20. Power control apparatus for a pneumatic dispatch system having a transmission line, comprising a valve, a pneumatic motor for opening and closing the valve,

means for initiating operation of the motor to open the valve upon the slight decrease in pressure in the transmission line incident to the introduction of a carrier therein, and independent means for initiating closing of the valve upon a slight increase in pressure in the transmission line due to delivery of a carrier from the latter.

Signed by me at Syracuse, New York this third day of July, 1923.

JAMES T. COWLEY.
